FIG. 5.

INVENTOR
MORTIMER MORTON
BY *A. B. Bowman*
ATTORNEY

UNITED STATES PATENT OFFICE

MORTIMER MORTON, OF LOS ANGELES, CALIFORNIA

TOY WINDMILL

Application filed March 31, 1930. Serial No. 440,318.

My invention relates to a toy windmill, and the objects of this invention are: first, to provide a toy windmill apparatus having a vane-wheel adapted to be driven by the wind and having in connection therewith a jointed figure, such as the figure of a person which is operatively connected with the vane-wheel in such manner that the jointed figure will appear to be rotating the vane-wheel when the latter is in fact rotated by the wind; second, to provide an apparatus of this class in which the several members of the jointed figure are pivoted with respect to each other by a crank means carried by the apparatus and in which the crank means is rotated at a slower rate of speed than the vane-wheel operating the same, thus giving slower movement to the members of the jointed figure so that the movements can be readily seen, the reduction in speed to the rotation of the crank means also increasing the life of the apparatus materially and preventing the figure from being torn to pieces readily, particularly when the vane-wheel is rotated by a high wind; third, to provide a structure of this class in which the jointed figure is relatively large and positioned considerably to one side so that the same is not materially obscured from view by the other members of the apparatus, particularly by the vane-wheel when the same is rotated; fourth, to provide a novel crank construction for an apparatus of this class; fifth, to provide as a whole a novelly constructed toy windmill apparatus; and, sixth, to provide an apparatus of the class which is very simple and economical of construction, durable, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon which form a part of this application in which:

Figure 1 is a front elevational view of my

toy windmill in one form of construction, showing fragmentally the supporting means therefor; Fig. 2 is a side elevational view thereof; Fig. 3 is a fragmentary sectional view thereof, taken through 3—3 of Fig. 1; Fig. 4 is a sectional view thereof taken through 4—4 of Fig. 2; and, Fig. 5 is a fragmentary sectional view similar to that shown in Fig. 3 but of a slightly modified form of construction.

Like characters of reference refer to similar parts and portions throughout the views of the drawings.

The operating members of my windmill, as shown in the drawings, are mounted upon a rotatable supporting means which is supported at the upper end of a preferably vertical support 1. The supporting means, in this instance, consists of a horizontal support 2 and a pair of uprights 3 and 4, one of the uprights extending upwardly from each end of the horizontal support 2. This horizontal support is rotatably mounted intermediate its ends, by means of a pin 5 or other suitable means, on the upper end of the vertical support 1, there being preferably provided a pair of washers 6 and 7 between the underside of the horizontal support 2 and the vertical support 1, as shown in Figs. 1 and 2, to provide stability and wear.

The vane-wheel, designated 11, is shown as made of sheet metal and is formed of one piece of sheet metal. In this instance, I have shown a plurality of vanes 11a which are formed at the ends of arms 11b, the arms being reinforced by turning the edges of the arms inwardly, forming inwardly extending flanges 11c, said arms also forming part of the inner ends and axial portion of the vanes for reinforcing the same, as shown. At the axial portion of the vane-wheel and between the flanges 11c may be secured a bushing or hub 12 for securing the vane-wheel to a shaft 13. The shaft 13, in this instance, is rotatably mounted on both of the uprights 3 and 4 and intermediate the ends thereof. The shaft 13 may be held against longitudinal movement relative to the uprights by means of a collar 14, secured at the outer side of the upright 3, and a small spur gear 15 secured

to the shaft at the opposite side of the upright 3 from the collar 14.

At the upper ends of the uprights are provided journals for rotatably supporting the crank means. The crank means in this instance consists of a pair of crank members 16 and 17, the former being mounted on the upright 3 and the latter on the upright 4. The crank or throw portions 16a and 17a of these crank members are aligned, as shown in Figs. 2, 3 and 5, and are connected with each other by a sleeve 18. On the crank member 16, around its axis of rotation, is secured a gear 19 which meshes with and is driven by the gear 15, the latter being considerably smaller than the former for reducing the speed of the crank means from that of the vane-wheel.

The jointed figure, above referred to, consists, in this instance, of the figure of a man. This figure is made essentially of five members, namely, a pair of leg members 21, a body member 22, and arm members 23. The leg members are secured in spaced apart relation to the horizontal support 2 and preferably at the opposite sides of its pivotal connection with the vertical support 1. These leg members extend angularly from and to one side of the horizontal support, as shown in Fig. 1. The body member 22 is pivotally connected at its lower end to the extended ends of the leg members and between the same, permitting the body member or the torso of the man, including the head, to move back and forth. The arm members 23 are positioned at the opposite sides of the body member and pivotally connected thereto at their outer ends at the shoulder portions of the body members. The other, or hand, ends of the arm members are pivotally connected to the sleeve 18. As the crank means is rotated, the hand ends of the arms move in a circular path, causing the upper portion of the body member to move back and forth and to give the appearance of the crank being rotated by the man or any other figure mounted in the relation described above.

Intermediate the ends of the upright support 4 is secured a horizontal support 26 which extends to one side in alignment with the axis of rotation of the vane-wheel. To the extended end of the horizontal support 26 is secured a rudder 27 for directing the vane-wheel into the wind.

In the modified structure shown in Fig. 5, the vane-wheel is connected directly to the crank member 16 at its axis of rotation, that is, coincident with the axis of rotation, the reduction gears being omitted in this instance. With this construction, the members of the figure move much more rapidly.

Though I have shown and described a particular construction, combination and arrangement of parts and portions, and a certain application thereof to toys and a certain

modification thereof, I do not wish to be limited to this particular construction, combination and arrangement, nor to the particular application, nor to the modification, but desire to include in the scope of my invention the construction, combination and arrangement substantially as set forth in the appended claims. 70

Having thus described my invention, what I claim as new and desire to secure by Letters Patent is:

1. In an apparatus of the class described, a rotatably mounted horizontal support, a pair of uprights rigidly secured at and to the opposite ends of said support and provided at their upper ends with horizontally disposed journals, a crank member rotatably mounted in each of said journals with the crank portions of each in alignment with each other, means for holding said crank portions in alignment, a vane-wheel operatively connected to one of the crank members, a rudder secured intermediate the ends of the upright in which the other crank member is mounted, and a pivotally jointed figure supported on said rotatably mounted horizontal support and pivotally connected with the aligned ends of said crank members. 80 35

2. In an apparatus of the class described, a rotatably mounted horizontal support, a pair of uprights rigidly secured at and to the opposite ends of said support and provided at their upper ends with horizontally disposed journals, crank means rotatably mounted in the journals and having a throw portion intermediate the uprights, a vane-wheel rotatably mounted intermediate the ends of the uprights with its axis of rotation parallel to the axis of rotation of the crank means, reduction gears connecting the vane-wheel with the crank means, a rudder carried by one of the uprights opposite the side at which the vane-wheel is positioned, and a pivotally jointed figure mounted on the support and pivotally connected with the throw portion of the crank means. 90 105

3. In an apparatus of the class described, a main vertical support, a horizontal support rotatably mounted thereon intermediate its ends, a pivotally jointed figure supported on said support directly over said main vertical support, a pair of uprights positioned on the extended ends of said rotatable support and provided at their upper ends with journal portions, a rudder rigidly secured to one of the uprights, a crank means rotatably mounted in said journal portions and operatively connected with said pivotally jointed figure, a vane-wheel positioned at one side of the other upright opposite said rudder, and gears operatively connecting said vane-wheel with said crank means. 115 120

4. In an apparatus of the class described, a supporting means rotatable about a vertical axis, a crank means rotatably mounted there- 125 130

on on an axis at a right angle to the rotating axis of the supporting means, a vane-wheel rotatably mounted on the supporting means with its axis of rotation at a right angle to the rotating vertical axis of the supporting means, gears operatively connecting the vane-wheel with the crank means, a jointed figure supported by the supporting means and operatively and pivotally connected to the crank portion of the crank means, and a rudder carried by the supporting means in substantial vertical alignment with the axis of rotation of the vane-wheel.

15 5. In an apparatus of the class described, a supporting means rotatable about a vertical axis, a crank means rotatably mounted thereon on an axis at a right angle to the rotating axis of the supporting means, a vane-wheel rotatably mounted on the supporting means with its axis of rotation at a right angle to the rotating vertical axis of the supporting means, reduction gears operatively connecting the vane-wheel with the crank means, a jointed figure supported by the supporting means and operatively and pivotally connected to the crank portion of the crank means, and a rudder carried by the supporting means in substantial vertical alignment with the axis of rotation of the vane-wheel.

20 6. In an apparatus of the class described, a supporting means rotatable about a vertical axis, a crank means rotatably mounted thereon on an axis at a right angle to the rotating axis of the supporting means, a vane-wheel rotatably mounted on the supporting means, the axis of rotation of the vane-wheel parallel to the axis of rotation of the crank means, reduction gears operatively connecting the vane-wheel with the crank means, a jointed figure supported by the supporting means and operatively and pivotally connected to the crank portion of the crank means, and a rudder carried by the supporting means in substantial vertical alignment with the axis of rotation of the vane-wheel.

25 7. In an apparatus of the class described, a supporting means rotatable about a vertical axis, a crank means rotatably mounted thereon, a vane wheel rotatably mounted on the supporting means with its axis of rotation substantially transversely to the rotating vertical axis of the supporting means, gears operatively connecting the vane-wheel with the crank means, a jointed figure supported by the supporting means and operatively and pivotally connected to the crank portion of the crank means, and a rudder carried by the supporting means at the opposite side of the vertical axis from the vane wheel.

In testimony whereof, I have hereunto set my hand at Los Angeles, California.

MORTIMER MORTON.
